US00D858773S

(12) **United States Design Patent** (10) Patent No.: **US D858,773 S**
(45) Date of Patent: ** Sep. 3, 2019

(54) **LINK FOR APPARATUS FOR TREATING BODY TISSUE SPHINCTER**

(71) Applicant: **Torax Medical, Inc.**, Shoreview, MN (US)

(72) Inventors: **Chad J. Kugler**, Buffalo, MN (US); **Jerome K. Grudem, Jr.**, Rogers, MN (US); **Todd A. Berg**, Stillwater, MN (US); **William J. Swanson**, St. Paul, MN (US)

(73) Assignee: **Torax Medical, Inc.**, Shoreview, MN (US)

(**) Term: **15 Years**

(21) Appl. No.: **29/627,842**

(22) Filed: **Nov. 30, 2017**

Related U.S. Application Data

(60) Continuation-in-part of application No. 14/445,723, filed on Jul. 29, 2014, which is a division of application No. 13/403,441, filed on Feb. 23, 2012, now abandoned, which is a division of application No. 12/610,633, filed on Nov. 2, 2009, now Pat. No. 8,187,164, which is a continuation of application No. 11/147,801, filed on Jun. 7, 2005, now Pat. No. 7,695,427.
